[57] CLAIM

The ornamental design for a bowl or similar article, substantially as shown and described.

DESCRIPTION

FIG. 1 is a side elevational view of a bowl or similar article showing my new design, the other side being a mirror image thereof;

FIG. 2 is a bottom plan view thereof;

FIG. 3 is a sectional view thereof taken along the lines 3—3 of FIG. 2, with the pattern as seen through the interior wall having been left out for ease of illustration; and

FIG. 4 is a top plan view thereof, with the pattern as seen through the interior wall having been left out for ease of illustration.

FIG. 1

FIG. 4
